CONTROL DEVICE FOR INDEXING AND PHOTOTRANSSCRIPTION MACHINES

Filed Aug. 10, 1939

UNITED STATES PATENT OFFICE

2,215,381

CONTROL DEVICE FOR INDEXING AND PHOTOTRANSRIPTION MACHINES

Leonard G. Townsend, Washington, D. C.

Application August 10, 1939, Serial No. 289,462

2 Claims. (Cl. 40—53)

(Granted under the act of March 3, 1883, as amended April 30, 1928; 370 O. G. 757)

The invention described herein may be manufactured and used by or for the Government of the United States for governmental purposes without the payment to me of any royalty thereon, in accordance with the provisions of the act of April 30, 1928 (ch. 460; 45 Stat. L. 467).

This invention relates to a control device for indexing and phototranscription machines.

An object of the invention is to improve on certain elements and means disclosed in my United States Patent #2,121,061 of June 21, 1938, in that I now provide a more simple and positive means for accurately stopping the record bearer or carrier at the registering station upon the breaking of an electrical circuit established by the operation and cooperation of the various parts described in the above mentioned patent.

A further object is to provide a reliable means for assuring that the operation of the machine may be resumed after the stoppage of the record carrier at the registering station and thereafter continued until such time as an appropriate circuit is again established to effect stoppage.

A still further object is to provide means whereby the starting of the machine in its next cycle may be conveniently effected by either manual or automatic control.

The single figure of the drawing is, for the most part, a reproduction of Figure 10 of Patent 2,121,061, and reference characters corresponding with those used upon the drawing of the patent are employed here in so far as is necessary to describe the parts of the instant structure that more immediately and directly cooperate with the parts of the patented structure.

This patent discloses a method of and apparatus for the indexing and phototranscription of records, and has for its object the provision of a machine for supplementing and extending the known art relating to the compilation, maintenance, and tabulation of records. In this art there has been developed a method of producing records microphotographically upon a film, and my patent referred to, among other things, discloses means for feeding the film to a registering station and stopping it for accurate registry at said station, for purposes stated in the patent, the stopping means including the shaft 621 rotating continuously during the operation of the machine until such time as it is desired to stop the film at the registry station. This shaft in the patent is shown as carrying the film feeding drum and also a disk 407 having stops 407' thereon to be engaged by a projection carried by a rod reciprocated continuously by a cam carried by the

disk, there being a notch in the rod to be engaged by a latch 402 carried by the armature of a magnet 400 to arrest the movement of the rod with its projection in the path of movement of a stop 407' on the disk, to stop the film at the registry station, the energization and deenergization of the magnet being controlled by a mechanism controlling various circuits.

In the present construction, I simplify the film stopping means by eliminating the reciprocating rod and the cam of the patent and produce an arrangement wherein the latch of the magnet 400 directly engages a stop on the disk 407, and provide an additional magnet for assuring that the operation of the machine may be resumed after the stoppage of the record carrier at the registry station until it is again stopped by establishing an appropriate circuit.

The figure is a circuit diagram of the machine of the patent above referred to, having associated therewith the improved control features forming part of the driving mechanism to effect the stoppage of the machine at the desired point or registering station, for viewing, projecting, photographing, and for other purposes.

Referring to the drawing, 621 designates the driving shaft of the machine, which shaft carries a feed driving drum 610, which shaft and drum may correspond in all respects to the similarly marked parts of the above mentioned patent. On this shaft is keyed the locking disk 407 provided at quarter intervals with a shouldered stop 407' normally out of the path of movement of a projection or latch 402 mounted on an armature 898. The armature is apertured for the passage of three similar rods 4, 5 and 6, upon which the armature can freely move. The rods are firmly secured to a suitable magnet base of insulating material or material from which they may be insulated. Between the armature and base are magnets 3 and 400 exerting, when energized, a pull on the armature against the tension of spiral springs 401 whose normal tendency is to keep the latch 402 projected into the path of movement of the stops on disk 407 when the magnets are deenergized. The magnets withdraw said armature and latch from latching position when either or both magnets are energized.

In operation, with a machine running at high speed, current is supplied to the motor (M) from main supply wire 110, motor terminal 117, through motor and terminal 116, to lead 115 and through contacts 112 and 113, which are now closed, back to main supply line 111. Current from supply wire 150 passes to lead 160, through

contacts 158 and 159, which are closed, through lead 162, through magnet 400 and back to supply wire 151. Magnet 400 is thus energized, attracting armature 898, causing the latch 402 carried thereby to be held out of the path of movement of a stop on disk 407; consequently, the disk is free to rotate, which it is continuously doing until such time as it is desired to stop a record at the registering station.

10 After a selection has been made and the record, a film in the present instance, has been run forward a predetermined distance or amount and then reversed and run back in the manner and by the means described in Patent #2,121,061, the 15 dwell 123a of cam 123 allows roller 135 carried by pivoted armature 137 to drop. This movement of the armature opens the contacts 158 and 159 which breaks the circuit through magnet 400, de-energizing said magnet and allowing the springs 20 201 to project the armature 898 to position wherein the latch 402 will be engaged by a stop 407', thus stopping the machine at the proper time and place. After stopping the record at the registering station, and after this operation has served 25 its purpose, whatever that may be within the possibilities of the contrivance, and when it is desired to again start the machine, this can be done either automatically or manually—automatically by closing contacts 226 and 228 by cam 30 227, and manually by the closing of switch 225. In either event the result is the resetting of the magnets 232, 242 and magnet 3, all of which are included in the reset circuit. Upon the energization of magnet 3, the armature 898 is attracted 35 against the tension of springs 201 and its latch 402 is withdrawn from the stop 407' of disk 407, allowing said disk to rotate.

Coincidental with the operation of the reset circuit just described, armatures 171a and 181a 40 were retracted by the magnets 190 and 191 through the resetting of the keyboard circuit explained in the patent hereinbefore mentioned. With retraction of armature 171a, contacts 112 and 113 were again closed; consequently starting 45 the motor in clockwise direction at high speed.

I claim:

1. In a machine of the character described, means for arresting the movement of a traveling record carrier at a definite point, including a normally continuously rotating shaft, record feeding 50

means actuated by said shaft, a member rotated by said shaft and provided with stops, two magnets, an armature common to both and provided with a latch for directly engaging a stop on said member to arrest the movement of said member, means for constantly urging the armature and consequently its latch toward the stop member, a different electrical circuit for each magnet through which said magnets are energized to hold the armature and its latch out of the path of movement of the stops and deenergized to make operative the means for urging the armature toward the stops to move the latch into the path of movement of the stops, one of said magnets operating to attract the armature to a disengaged 10 position while the stop member is rotating and the other magnet operating to disengage the stop-engaging means from the stop when said stop member is stationary, thereby assuring the resumption of operation of the machine after stoppage of the record carrier at a definite point.

2. In a machine of the character described, means for arresting the movement of a traveling record carrier at a definite point, including a normally continuously rotating shaft, record feeding 25 means actuated by said shaft, a member rotated by said shaft and provided with stops, two magnets, an armature common to both and provided with a latch for directly engaging a stop on said member to arrest the movement of said member, means for constantly urging the armature and consequently its latch toward the stop member, a different electrical circuit for each magnet through which said magnets are energized to hold the armature and its latch out of the path of movement of the stops and deenergized to make operative the means for urging the armature toward the stops to move the latch into the path of movement of the stops, one of said magnets operating to attract the armature to a disengaged 30 position while the stop member is rotating and the other magnet operating to disengage the stop-engaging means from the stop when said stop member is stationary, thereby assuring the resumption of operation of the machine after stoppage of the record carrier at a definite point. 35

2. In a machine of the character described, means for arresting the movement of a traveling record carrier at a definite point, including a normally continuously rotating shaft, record feeding 40 means actuated by said shaft, a member rotated by said shaft and provided with stops, two magnets, an armature common to both and provided with a latch for directly engaging a stop on said member to arrest the movement of said member, means for constantly urging the armature and consequently its latch toward the stop member, a different electrical circuit for each magnet through which said magnets are energized to hold the armature and its latch out of the path of movement of the stops and deenergized to make operative the means for urging the armature toward the stops to move the latch into the path of movement of the stops, one of said magnets operating to attract the armature to a disengaged 45 position while the stop member is rotating and the other magnet operating to disengage the stop-engaging means from the stop when said stop member is stationary, thereby assuring the resumption of operation of the machine after stoppage of the record carrier at a definite point.
